PATENTED JUNE 6, 1834.

8237X. S. M. HANDY, J. ALBEE & E. B. CUTTS.

MILL FOR GRINDING CORN AND OTHER GRAIN.

June 6, 1834

Samuel M. Handy, John Albee & Enoch D. Cutts

Setters Patent

6237X

The Schedule referred to in this Setters Patent and making part of the same containing a description in the words of the Said Samuel M. Handy, John Albee & Enoch D. Cutts, themselves, of their improvement in the mode of Constructing Mills for grinding Corn and other grain.

To all whom these presents shall come, Be it known that we, Samuel M. Handy, John Albee and Enoch D. Cutts, all of Hollisville in the County of Penobscot and State of Maine, have invented a new and useful improvement in the mode of Constructing Mills for grinding Corn and other grain, and that the following is a full and exact description of the Construction and operation of the said Machine as invented or improved by us. The general appearance of the Machine is represented in the accompanying drawings. Ct frame is first built Ct 1 represents the Sills which are about two and a half feet long Ct 2, 2, 3, 4, represent four posts which are fastened to the Sills by tenons which are made at the foot of the posts entering of Mortises corresponding in the Sills.

Ct 2, 2, are three and three fourths high nine or ten and Ct 3, 3 feet high Ct 4 is a plank one foot in width which is spiked on to two of the posts on the back side of the Machine Ct 5 is a plank of the same size spiked on to the front posts Ct 6 is a bar with a tenon in either end which enters a Mortise in the side of the post about two and one half feet from the foot of the post, and is about ten feet long Ct 7 is a bar connecting the two posts of the frame at the other end Ct 8 is a bar which lies upon the bar before mentioned and is placed upon the same by two bars at the other end of them. These bars support the Mill Stones Ct 1, 8, 8.

The Stones Nos. 8, 8, are about twenty two inches deep upon the top, and nineteen inches deep, and are of an equal size. That is to say the distance from the top of both of the stones, is twenty two inches more or less Ct 9 is the hopper into which the Corn or grain is put Ct 10 is a small wheel about eleven inches in diameter which plays upon a shaft to

8037X

June 6, 1834

which passes through in the middle between the two stones 88, which cog wheel is turned by another large cog wheel Ctr. 11 about 3 feet in diameter. The wheel Ctr. 11 plays upon a shaft Ctr. 13 and is turned by a crank Ctr. 12. Both of the shafts rest one end upon the top side of the plank No. 5 and the other end passes through the plank Ctr. 4, Ctr. 14 & a small wheel about 3 feet in diameter which is attached to one end of the shaft Ctr. 14 is a shaft which passes through a cylindrical block of No. 5 a cylindrical stone about fourteen inches long and four and one half inches in diameter at the large end and twelve inches in diameter at the other which plays into a cavity exactly similar to that in the other stone 8.

The lay of this County Mill is each of the stones 88. Exposed to one side of this County and the other side of the box in which the shafts play at County exactly similar to that in the other stone 8.

Represents the opening through which the Cane is carried to the revolving stone of 88 an opening which lies the same distance from the middle in the opposite end and side of the stone from where a is situated.

What we claim is the use and of our stone in connection with the peculiar form of the stones and the particular application of said stones and their arrangement as above specified and described.
